(57) **CLAIM**

I claim the ornamental design for a dodo bird novelty, as shown and described.

DESCRIPTION

FIG. 1 is a right side elevational view of my dodo bird novelty with the left side elevational view being a mirror image thereof;

FIG. 2 is a top view thereof;

FIG. 3 is a front view thereof; and,

FIG. 4 is a rear view thereof.

The portions shown in broken lines are for illustrative purposes only, and form no part of the claimed design.

1 Claim, 2 Drawing Sheets

FIG. 3

FIG. 4
